UNITED STATES. PATENT OFFICE.

SAMUEL H. THOMSON, OF DAYTON, OHIO, ASSIGNOR TO THE S. H. THOMSON MANUFACTURING COMPANY, OF DAYTON, OHIO.

SPOT LAMP FOR AUTOMOBILES AND THE LIKE.

1,426,023.

Specification of Letters Patent. Patented Aug. 15, 1922.

Application filed December 27, 1921. Serial No. 525,146.

To all whom it may concern:

Be it known that I, SAMUEL H. THOMSON, a citizen of the United States, residing at Dayton, in the county of Montgomery & 5 State of Ohio, have invented certain new and useful Improvements in Spot Lamps for Automobiles and the like, of which the following is a specification, reference being had therein to the accompanying drawings.

10 This invention relates to spot lamps for automobiles, and the like, having particular reference to improvements in spot lamps of the type illustrated and described in my copending application for Letters Patent, filed September 22, 1921, Ser. No. 502,451.

The main feature of advantage in spot lamps of this character consists in their wide range of adjustment,—the lamps being adjustable in both horizontal and vertical planes of rotation, or in any two given planes of rotation at right angles one to the other. Thus the range of light projection, by a combination of the double adjustment, is practically universal,—that is to say the 25 lamps can be adjusted to project the light at any desired angle.

To comply with certain traffic regulations, and out of consideration for drivers of automobiles, and the greater safety of those 30 who ride in them, means are provided in the present invention to limit the angular adjustment of the spot lamp so that its rays cannot be directed, accidentally or otherwise, full in the face of the driver of an 35 automobile approaching from the opposite direction. In certain of the States adjustment of spot lights in this respect is regulated by statute, and is a safeguard that should be universally enforced so far as 40 practicable.

The construction of the spot light, as herein shown to illustrate the invention, is substantially the same as that shown and described in my copending application, except 45 as to the means for limiting the angular adjustment of the lamp, and does not require detailed explanation, therefore, except as to the added feature.

In the accompanying drawing:

50 Fig. 1 is a side elevation of the spot lamp having the cover cap removed from the gear case, and showing the means employed for

limiting the angular adjustment of the lamp.

Fig. 2 consists of two detail views of the adjustment controlling means detached.

As here shown, the lamp fixture as a whole consists of the spot lamp —1 which is pivoted in a bracket or housing —3 by means of an L-shaped arm —2, the arm being hollow to receive the electrical cord —4. Rotary horizontal adjustment of the lamp is effected by means of bevel gears —5—6, gear —5 being secured to the portion of the arm —2 extending into the bearing 60 housing —3, and gear —6 being secured to a shaft —7 which is connected to the lamp adjusting handle —8, shaft —7 and a tube —9, secured to the housing —3 at one end and cooperating with the operating handle 70 at its opposite end to effect rotary vertical adjustment of the lamp, being arranged concentrically in an outer stationary tube —10 by means of which and a suitable bracket the lamp is adapted to be mounted 75 on an automobile. Tube —9 has a sleeve —11 secured to its end adjacent the operating handle —8, and is adapted to be engaged with a notched disc —12 secured to the stationary tube —10 by means of a latch 80 —13 pivoted in sleeve —11. The operating handle —8 is connected to sleeve —11 by means of a clutch —14, and has sufficient axial movement on shaft —7 to disengage the clutch and permit of operating gears —5 85 and 6 to adjust the lamp in the horizontal plane. To adjust the lamp in the vertical plane, latch —13 is disengaged from disc —12, and handle —8 is manipulated without disengaging the clutch.

90 From the foregoing brief description it will be understood that the spot lamp of the present invention, as that of my earlier invention herein referred to, is adapted for universal angular adjustment, except that 95 in the present case, means are employed to limit the angular adjustment of the lamp in a horizontal plane.

The means for limiting the movement of gears —5 and 6, as here shown, consists of a 100 spring clip, shown in detail in Fig. 2, and as applied to the gears in Fig. 1. The clip has a circular spring portion —15 adapted to fit the hub of gear —5 and an up-turned

portion —16 adapted to fit between two opposite teeth of the gear, thus the gears at this point will lock one with the other and further movement in one direction will be prevented. It will be obvious that the clip can be adjusted in any position relative to the gear, and that the horizontal angular adjustment of the spot lamp can thus be regulated as desired to meet traffic conditions and statute requirements.

Having described my invention, I claim:

1. In spot lamp controlling means, the combination of a pivotally mounted lamp, intermeshing gears and means for operating the same to effect angular adjustment of said lamp, and means mounted and variably adjustable relative to one of said gears, and adapted to engage with the other gear to limit said adjustment of the lamp in a given direction.

2. In a spot lamp controlling means, the combination of a pivotally mounted lamp, intermeshing gears and means for operating the same to effect angular adjustment of said lamp, and means detachably secured to one of said gears and adapted to rotate

therewith and engage with the other gear to limit said adjustment of the lamp in a given direction.

3. In a spot lamp controlling means, the combination of a pivotally mounted lamp, intermeshing gears and means for operating the same to effect angular adjustment of said lamp, and a spring clip adapted to engage the hub of one of said gears and having an up-turned portion adapted to engage the teeth of both of said gears to limit said adjustment of the lamp in a given direction.

4. In a spot lamp controlling means, the combination of a pivotally mounted lamp, intermeshing gears and means for operating the same to effect angular adjustment of said lamp, and a spring clip adapted to engage the hub of one of said gears and to be variably adjusted thereon, and having a portion adapted to lock between the teeth of the opposite gears to limit the said adjustment of the lamp in a given direction.

In testimony whereof, I affix my signature.

SAMUEL H. THOMSON.
